(57) **CLAIM**

The ornamental design for an apparatus for restraining hand digit contact with the face, as shown and described.

DESCRIPTION

FIG. 1 is a top, perspective view of an apparatus for restraining hand digit contact with the face showing the new design in accordance with an aspect of the subject technology;

FIG. 2 is a front edge view of the apparatus of FIG. 1;
FIG. 3 is a rear edge view of the apparatus of FIG. 1;
FIG. 4 is a left, end view of the apparatus of FIG. 1;
FIG. 5 is a right, end view of the apparatus of FIG. 1;
FIG. 6 is a top view of the apparatus of FIG. 1; and,
FIG. 7 is a bottom view of the apparatus of FIG. 1.
The broken lines crossing claimed surfaces depict stitching and form no part of the claim. The broken lines along the perimeter of the straps depict stitching and form no part of the claim. All other broken lines depict portions of the article and form no part of the claim.

1 Claim, 4 Drawing Sheets
